(57) **CLAIM**

The ornamental design for a beam clamp, as shown and described.

DESCRIPTION

FIG. 1 is a front, top perspective view of a beam clamp showing our new design;

FIG. 2 is a right side view thereof;

FIG. 3 is a front view thereof;

FIG. 4 is a bottom view thereof;

FIG. 5 is a top view thereof;

FIG. 6 is a rear view thereof;

FIG. 7 is a rear, top perspective view thereof;

FIG. 8 is a front, bottom perspective view thereof; and,

FIG. 9 is an exploded front, bottom perspective view thereof.

The dashed broken lines in the figures illustrate portions of the beam clamp that form no part of the claimed design.

1 Claim, 7 Drawing Sheets
